J. FRAIDUS,
AUTOMOBILE RADIATOR.
APPLICATION FILED NOV. 25, 1919.

1,400,353.

Patented Dec. 13, 1921.

FIG. 1.

FIG. 2.

FIG. 3.

Inventor

Joe FRAIDUS

By his Attorney

Morris Auerbach

UNITED STATES PATENT OFFICE.

JOE FRAIDUS, OF NEWARK, NEW JERSEY, ASSIGNOR TO SAMUEL SCHNIPER, OF NEW YORK, N. Y.

AUTOMOBILE-RADIATOR.

1,400,353.

Specification of Letters Patent. Patented Dec. 13, 1921.

Application filed November 25, 1919. Serial No. 340,553.

To all whom it may concern:

Be it known that I, JOE FRAIDUS, subject of the Government of Russia, and resident of Newark, in the county of Essex and State 5 of New Jersey, have invented certain new and useful Improvements in Automobile-Radiators, of which the following is a specification.

This invention relates to radiators for 10 cooling the circulating liquid of cooling systems for internal combustion engines such as used in automobiles.

The object of this invention is to provide 15 a radiator of the character described which shall be strong and durable, afford a large liquid capacity, and a high degree of cooling efficiency.

Another object of this invention is to provide 20 a radiator of the character described which shall have the advantages aforesaid and yet be cheap to manufacture, simple and compact in construction and easy to repair.

Other objects and advantages of this invention will appear from the detailed description and the features of novelty will 25 be particularly pointed out in the claims.

In the drawing accompanying this specification and forming a material part thereof,

30 Figure 1 is a perspective view of a radiator core embodying my invention viewed along line 1—1 of Fig. 2.

Fig. 2 is a plan view of the core section shown in Fig. 1;

35 Fig. 3 is a fragmentary perspective view showing two complementary corrugated sheets used in assembling the core; and

Fig. 4 is a fragmental detailed section taken along line 4—4 of Fig. 2.

40 Referring in detail to the drawing, the radiator core comprises a series of tortuous spaces or conduits 10 for the circulating liquid, the walls of which form air tubes 11 through which the air is blown. These

45 water channels 10 and air tubes 11 are constructed in the following manner. A plurality of sheets of thin metal are corrugated by a rolling process so as to provide zig-zag units such as shown in Fig. 3 having

50 a series of alternately parallel horizontal faces 12 running at an angle in one direction and a series of alternately parallel horizontal faces 13 running at an angle to the direction of said first series of faces, the corresponding faces of the series 12 and 13

being adjacent to each other and meeting in a vertical flat rib 14, as will be clear from Fig. 3. The upper and lower ends of these sheets are indented to form a ridge 15 and small portions 16 offset from the faces 60 12 and 13. These offset portions meet in a sharp edge 17. In assembling the radiator core sections made from four such sheets are constructed in the following manner: Two such sheets 18 and 19 are placed together with the vertical faces 12 and 13 on each of the sheets running in opposite directions and these are soldered together along the sharp edges 17 as at 20, so as to inclose therebetween the substantial trapezoidal 70 tubes 11. Complementary sheets 22, 23 are then placed on either side of the two sheets such as 18 and 19 already secured together in the manner aforementioned, so that each of said complementary sheets is in registry 75 with the outer walls of the air tubes 11 as will be readily understood. In this manner the corresponding offset portions 16 on the sheets 18, 19, and 22, 23 respectively meet to form a close fit at their top and bottom 80 ends, while by reason of the offsetting of the faces 12 and 13 from these ends as hereinbefore described a tortuous channel or conduit 10 is provided between the air tubes 21 and these outer sheets 22 and 23. 85

The complementary sheets 22 and 23 will now serve each as one-half or a semi-section of further tubes 21 formed by soldering to each of them corresponding sections in the manner already described with reference to the securing together with sheets such as 18 and 19. Complementary sections are then secured on the outer faces of the additional tubes 21 so formed and in registry therewith to form additional channels 90 10 in the manner described with reference to sheets 22 and 23. This process is repeated until a radiator core of any desired size is obtained. 95

Having thus described my invention, I 100 claim as new and desire to secure by Letters Patent:

1. A radiator comprising a plurality of rows of tubes formed from sheets of metal, said sheets being corrugated to provide a 105 series of parallel inclined faces and another series of parallel inclined faces alternating with said first mentioned series and running at an angle thereto, the widths of one of said series of parallel faces being sub- 110

stantially greater than the widths of the other alternate series of parallel faces so as to form substantially trapezoidal air openings when said sheets are placed together, 5 said sheets being indented at the upper and lower ends thereof to form offset portions whereby two such complementary sheets unite at their lower and upper ends to form a close fit and inclose between the faces 10 thereof a tortuous channel for the liquid to be cooled.

2. A radiator comprising a plurality of core sections suitably joined together, each of said sections comprising a pair of corrugated sheets of metal having a series of inclined faces and another series of parallel inclined faces alternating with said first mentioned series and running at an angle thereto, the width of the face of one of said 15

series being substantially greater than the 20 corresponding width of the other alternate series, said sheets being indented at the upper and lower ends thereof to offset portions, meeting in a sharp edge, said pair of sheets being arranged with their offset portions in registry with each other and united at their said offset portions to inclose between the parallel faces thereof a tortuous channel for the liquid to be cooled, and another such pair of united sheets arranged in 25 opposed relation to said first mentioned pair and joined thereto on the sharp edges of the offset portions so as to inclose a substantial trapezoidal air opening.

Signed at New York city, in the county 30 of New York and State of New York, this 29th day of October, A. D. 1919.

JOE FRAIDUS.
